UNITED STATES PATENT OFFICE

ALBERT J. MILLIGAN, OF SAN FRANCISCO, CALIFORNIA

GAS APPLIANCE

Application filed February 18, 1929. Serial No. 340,952.

This invention relates to improvements in gas appliances and more particularly to gas saving attachments to gas burners.

Among the objects of the invention are to insure efficient use of the gas burner, by automatically shutting off the gas supply when the burner is not in use and automatically turning on the gas and igniting the burner when heat is desired, in combination with manual control and regulation of the gas supply to the burner.

Another object is to conserve the time of cooks, more especially in restaurants, where much time is lost in regulating the gas for different kinds of fry orders requiring different volumes of heat. Other objects and advantages will appear as this description progresses.

With this invention applied to several burners, the burner adjusted to the desired volume can be chosen and the utensil set upon it without further attention until the food is cooked. One of the advantages of this invention is lowering the temperature in small kitchens during the rush hours, since only those burners actually used for cooking are ignited. It is an established fact that few cooks will turn off a burner after they are through with it, accounting for waste heat often as high as 50% over that required in actual cooking.

In this specification and the annexed drawing the invention is illustrated in the form considered the best, but it is to be understood that it is not limited to such form, because it may be embodied in other forms, and it is also to be understood that in and by the claims following the description it is desired to cover the invention in whatsoever form it may be embodied.

In the accompanying one sheet of drawings: Fig. 1 is a side elevation of a gas stove partly in vertical section, having this invention applied to the burner thereof.

Fig. 2 is an enlarged detail in side elevation partly in vertical section, of the combined automatic and manual control valve forming part of this invention.

Fig. 3 is an end view of the same partly in

cross-section to illustrate the pilot light regulating valve.

In detail the construction illustrated in the drawings, referring to Fig. 1, comprises the stove top 1, supported upon the vertical walls 2 in the usual manner, with the open grid 3 over the burner. The burner comprises the mixing chamber 4, the throat 5 and the aspirator 6. The burner mixing chamber is spaced beneath the grid 3 and supported on the transverse bar 7 at the rear. The aspirator 6 is provided with the usual center hole engaging the nozzle 8 of the service cock having the nipple 9 that is screwed into the service pipe 10. This combination comprises the conventional gas shelf or gas stove top, to any type of which this invention is applicable.

Intermediate the nozzle 8 and the nipple 9 the valve has a transverse cylindrical body 11. This body is drilled to receive the sliding plunger 12 which acts as a valve closing the longitudinal bore 13 through the nozzle and the stem 9. To reduce friction on the flowing gas and increase its volume the bore 13 is counter-bored at 14, from the end of the nipple 9 up to near the plunger 12.

This plunger extends upward flush with the top of the lug 15 of the body and is surrounded by the overhanging washer 16 secured by the screw 17 threaded into the end of the plunger, see Fig. 2. The plunger extends through the lower lug 18 of the body and is provided with the adjustable collar 19 fixed thereon by the set screw 20.

The expansive spring 21 is introduced between the collar 19 and the end of the lug 18, whereby the washer 16 normally is held against the top of the lug 15 and the gas maintained in the shut-off position as shown in Fig. 1. This plunger is provided with an annular groove or passage 22 adapted to be brought into registry with the longitudinal hole 13 to permit a free flow of gas through the nozzle when the plunger is elevated to the position shown in Fig. 2. A hole through the plunger 12 would serve the same purpose as the groove 22, but would require means to insure registry with the hole 14.

The automatic control of the valve consists

of the extension 23 integral with the body 11, to which the bracket 24 is screwed, to support the fulcrum 25 for the operating lever 26. The outer end of this lever is twisted on itself at 90 degrees at the point 27, and has the adjustment screw 28 threaded therein, bearing beneath the plunger 12 so that the teetering of the lever 26 on the fulcrum 25 will raise and lower the plunger 12.

10 The inner end of the lever 26 is provided with the adjustable clamp 29, secured by a screw through the lever 26, to lock the clamp at any desired position on the lever 26 in the adjustment holes 30.

15 The vertical trip stem 31 is set in the clamp by the set screw 32, and is adjustable as to height and angle by the screw 32. The upper end 33 of this trip is adjusted to project slightly above the grid 3 so that when depressed flush with the top thereof the opposite end of the lever 26 will lift the plunger to bring the groove 22 into registry with the longitudinal hole 13 through the valve, permitting the maximum flow of gas from the service pipe 10. The tension of the spring 21 is such that the weight of a light utensil placed upon the grid 3 will depress the trip 33 as described.

20 To manually regulate the desired flow of gas from the service pipe 10 to the valve, I provide the operating handle 34 fixed to the top of a hollow sleeve 36, threaded on the lug 15 of the valve, whereby the rotation of the handle 34 upward permits the plunger 12 to rise to the extent that the handle is turned, thus giving a manual control of the volume of gas passing through the valve independent of the automatic control of the valve through the trip 33 and assembled mechanism.

25 The admission of air to the aspirator 6 is controlled by the usual louver 37 rotatable upon the nozzle 8. Adjustment of the louver is fixed by the set screw 38 passing through a segmental slot in the louver and threaded into the diaphragm of the aspirator front, in the usual manner.

30 The pilot light for igniting the burner comprises the small tube 39 fixed into a transverse hole passing through the side of the valve body 11 and communicating with the longitudinal counter bore 14 intermediate the service pipe 10 and the valve plunger 12, so that gas service to the pilot is independent of the valve control to the gas burner.

35 A vertical pilot valve plug is closely fitted into a vertical hole in the body 11. This plug is provided with a transverse valve hole 40 adapted to register with the transverse hole into the bore 14. The upper end of this pilot valve is bent to form the handle 41.

40 The outer end of the pilot 39 is brought into proximity to the burner mixing chamber 4 from which the flame emerges and is adapted to light the burner when the gas flow is admitted thereto through the nozzle 8. The amount of the flame issuing from the pilot

may be regulated by the manual adjustment 41. Pilot lights, not of the Bunsen type, burn with a yellow flame which blackens the utensils which it contacts. Such pilots also become encrusted at the tip which eventually closes. This difficulty is overcome by forming the stricture 39' near the end. This stricture forms a chamber near the choked tip of the pilot which becomes heated by the pilot flame and from the adjacent burner 4, forming in effect a retort within which the gas is regenerated so that the gas issuing therefrom burns clean and blue as a Bunsen flame.

45 Where the mixing chamber 4 of the burner has a center opening the trip 33 is preferably extended upwardly therethrough as in Fig. 1.

50 This invention operates substantially as follows: The pilot light 39 is ignited to throw a flame across the top of the mixing chamber 4, as regulated by the pilot valve 41. When the stove is to be used, the handle 34 is turned into the position shown in Fig. 2 which lets the plunger 12 rise to the maximum height and permits the gas to flow past the annular groove 22 and through the longitudinal opening 13 in the nozzle 8 and into the throat 5 of the burner. The aspirating effect of the issuing gas draws air through the louver 37, the mixture passing into the mixing chamber 4 from whence it issues through the jets of 55 the burner, being ignited by the pilot flame from 39, when there is a utensil resting on the top of the trip 33.

55 When the utensil is lifted or removed the expansion of the spring 21 forces the plunger 12 downward moving the annular groove 22 out of registry with the hole 13, shutting off the gas completely. When the utensil is replaced the operation is reversed and the full flow of gas again passes through the burner to be 60 again ignited by the pilot, the amount of gas being regulated by turning the handle 34. To regulate the rise of the plunger 12, the washer 16 fixed on the upper end thereof impacts against the top of the opening within the adjustable hollow sleeve 36.

65 Flat utensils with handles, such as fry pans, do not rest level on the grid 3 due to the over balance of the handles, and would not therefore turn the gas full on. This is corrected by the extension 33a, on the trip which catches the utensil off center and fully depresses the trip.

70 Having thus described this invention what I claim and desire to secure by Letters Patent is:

1. In combination with a gas stove adapted to support a utensil; a gas burner; a service valve having a longitudinal hole therethrough and a transverse plunger slidable in said valve and having a passage registerable with said hole; automatic means operated by said utensil for operating said plunger, and manual means for operating said plunger.
2. In combination with a gas stove adapted

to support a utensil; a gas burner; a service valve having a hole therethrough and a transverse plunger slidable in said valve and having a passage therein; a spring and stop adapted to normally hold said passage and hole out of registry; a lever pivoted on said stove having one end engaging said plunger and the other engaging said utensil and a pilot tube extending from said valve to said burner and having a nozzle end and a chamber in said tube adjacent said end.

3. In combination with a gas stove adapted to support a utensil; a gas burner; a service valve having a hole therethrough and a transverse plunger slidable in said valve and having a passage therein; a spring and stop adapted to normally hold said passage and hole out of registry; a lever pivoted on said stove having one end engaging said plunger and the other engaging said utensil and a handle screwed on said valve engaging the end of said plunger.

In testimony whereof I have hereunto affixed my signature.

ALBERT J. MILLIGAN.
